STATION INDICATOR

Benjamin B. Kirby, Kansas City, Mo.

Application January 13, 1951, Serial No. 205,911

1 Claim. (Cl. 40—42)

This invention relates to improvements in railway station indicators and has particular reference to a station indicator suitable for indicating to the mail clerk the approach of the train to a non-stop mail station.

On most railway systems where mail is carried, provision is made for the smaller non-stop stations where mail is picked up mechanically and delivered manually. When these non-stop stations are being approached the mail clerk must have some indication of the location of said station so that he may be able to deliver the mail pouch within a predetermined zone relative to said station. By means of this railway station indicator the mail clerk will be notified either audibly or visually of the train's approach to the station so that he will have sufficient time to properly position the pick-up mechanism and to deliver the mail pouch in the prescribed zone.

The principal object of the present invention is the provision of a station indicator that will automatically indicate the approach of a train to certain stations throughout its entire run or division.

Another object of this invention is the provision of a means for indicating the approach to stations, directly interconnected with and driven by the rotating car axle.

A further object of the present invention is the provision of a station indicating film provided with station indicating indicia and adapted to be driven in either of two directions across the face of the indicator whereby to indicate to the mail clerk the approach of the train to the station from either of two directions.

Another object of this invention is the provision of a station indicator having a movable tape and having resilient means whereby the tension is maintained substantially constant.

A still further object of the invention is the provision of a station indicator having driving means whereby an indicating tape is driven in synchronization with the forward speed of the railway car including manually operable means, whereby the tape may be freed from said driving means for relative adjustment thereto.

Other objects are simplicity and economy of construction, ease and efficiency of operation, and adaptability for adjustment to properly indicate the approach of the train to a certain station regardless of the number or length of the detours made by the train in its travel.

With these objects in view, as well as other objects which will appear during the course of the specification reference will now be had to the drawings wherein;

Fig. 1 is a front elevation of a railway station indicator for railway cars showing diagrammatically its drive connection with the railway car, and embodying this invention.

Fig. 2 is an enlarged plan view of the station indicator with some of the parts deleted.

Fig. 3 is an enlarged front elevational view of the station with some of the cover parts removed.

Fig. 4 is an enlarged rear view of the station indicator showing some of the driving mechanism and with some parts broken away.

Fig. 5 is an enlarged fragmentary sectional view taken on line V—V of Fig. 4.

Fig. 6 is a fragmentary enlarged sectional view taken on line VI—VI of Fig. 5.

Fig. 7 is a sectional view taken on line VII—VII of Fig. 3 with some parts left in elevation and other parts deleted.

Fig. 8 is an enlarged fragmentary view of the driving means with parts broken away.

2

Fig. 9 is an enlarged view taken on line IX—IX of Fig. 3.

Fig. 10 is a sectional view taken on line X—X of Fig. 9.

Fig. 11 is a diagrammatical view of the driving drums which are adapted to move the tape at a relative low rate of speed.

Fig. 12 is an enlarged sectional view taken on line XII—XII of Fig. 3.

Fig. 13 is a sectional view taken on line XIII—XIII of Fig. 12.

Fig. 14 is an enlarged sectional taken on line XIV—XIV of Fig. 7.

Fig. 15 is a diagrammatic view of the electrical circuit by which the station indicator is controlled.

Throughout the several views of the drawings like reference numerals refer to similar parts, and the numeral 2 designates a housing or cabinet of substantially rectangular form and having a removable cover member 4 secured to cabinet 2 by nuts 5 to facilitate adjustment and positioning of parts within the cabinet.

The reversible indicating tape 6 is provided along its opposite edges with a series of like slots 8 adapted to receive teeth 10 mounted on the periphery of driven drums 12 and 13 around which tape 6 passes to extend in a substantially horizontal planar position between two transparent plates 14 and 16.

Plate 14 is carried by a bracket 18 positioned on the front side of cabinet 2, while member 16 is securely attached along its rear edge to cabinet 2 and is disposed in spaced apart relation slightly above member 14 to permit the tape 6 to freely pass therebetween, furthermore the space between 14 and 16 extends to the forward edge of member 16 whereby said tape 6 may be positioned therebetween from the front side.

Below plate 14 is a compartment 20 containing an electric lamp 22 which serves to illuminate the plate and to clearly outline the indicia on tape 6. A shield 26 is so mounted in compartment 20, as to prevent the direct light from lamp 22 from being directed against said indicia. The lower wall 28 of compartment 20 is provided with an open vent 30 whereby air is permitted to circulate about lamp 22 whereby it is cooled.

Referring to Fig. 1 it will be noticed that in this view a live car axle 32 is provided with a fixed drive gear 34. Car axle 32 carries a bearing plate 36 on which is carried a spur gear 38 disposed to mesh with gear 34. Shaft 40 mounted for rotation in bearing plate 36 is operatively connected to drive the flexible shaft 42 which is interconnected with shaft 44 by means of coupling 46. Shaft 44 is rotatably mounted in bracket 48 which is secured to housing 2. Shaft 44 extends upwardly through an operating arm 50 and is provided thereabove with a rigidly attached pinion 52. The forward portion of bracket 48 is arcuate and notched at 54, 56 and 58 to receive a tooth 60 by means of which the operating arm is secured in any one of three positions. Tooth 60 is slidably carried by operating arm 50, and is normally urged to the latched position by means of compression spring 62 and is removable from the latched position by means of hand grip 63. When the tooth 60 is in notch 56 and the power is turned on, the tape 6 will remain at rest. Mounted for rotation on arm 52 is a gear wheel 64 which is in mesh with pinion 52, also rotatably carried by arm 50 is a gear wheel 66 which is in mesh with gear wheel 64 whereby when gear 64 is rotated by pinion 52 gear wheel 66 in one direction 66 will be rotated in the opposite direction. Mounted in parallel relation with shaft 44 is a shaft 68 which is rotatably mounted in the lower and upper leg of bracket 48 as clearly shown in Fig. 3. Rigidly mounted on shaft 68 is a spur gear 70 which is in operative alignment with gears 64 and 66 so that when operating arm 50 is moved to a position with tooth 60 in notch 54 gear 64 will be in operative engagement with gear 70 to drive shaft 68 in one direction, and when arm 50 is moved to a position with tooth 60 in notch 58 then gear 64 will be moved out of engagement with gear 70 and gear 66 will be moved in mesh with gear 70 to drive the shaft 68 in the opposite direction of rotation. When tooth 60 is positioned in notch 56 then both gears

75

78

80

64 and 66 will be positioned free from gear 70, thus permitting the free rotation of shaft 44 without driving shaft 68.

The body of shaft 68 is hexagonal in cross section and is adapted to carry a longitudinally adjustable drive wheel 72 which is provided with a suitable friction tire 74.

The hub of wheel 72 is provided with an annular groove 76 which is adapted to receive the shifting arm 78 which is rotatably mounted on nut 80. Nut 80 is rotatably mounted on a threaded shaft 82 which is rotatably mounted in the upper and lower legs of bracket 48 in parallel relation to shaft 68. This shaft is secured against longitudinal movement and is provided at its lower end with a thumb wheel 84 by means of which the nut may be operated to adjust the drive wheel 72 vertically on its shaft.

Referring to Fig. 7 reference is had to drive shaft 86 which is rotatably carried by housing 2, and is provided at its inner end with drive sprocket 88 in housing compartment 90, and outside said compartment with a worm wheel 92 which intermeshes with a worm 94 tangentially carried by a bracket 96 mounted for arcuate movement on shaft 86 as clearly shown in Fig. 8. The lower end of worm shaft 98 carries a frusto-conical wheel 100 which is securely attached thereto by means of set screw 102. The frusto-conical surface 104 of wheel 100 is urged against friction tire 74 by means of extension spring 106 which is attached at its one end to pin 108 mounted in housing 2 and at its other end to pin 110 mounted in bracket 96.

By adjusting thumb wheel 84 it is apparent that the relative rate of rotation of shafts 68 and 98 may be adjusted to properly indicate the position of the train on the track relative to a given railway station as shown on tape 6.

For permitting manual setting of the tape to properly indicate the position of the train along the track the following means is provided. Drive shaft 86 is provided at its forward end portion with a hand grip 112 which is securely attached by means of set screw 114. Hub 116 of worm wheel 92 is provided with a series of sockets 118 formed parallel with shaft 86 adapted to receive pins 120 mounted on the inner face of sleeve 122 which is slidably mounted on shaft 86 and adjustable longitudinally therealong by means of a stem 124 which is secured thereto by means of a cross pin 126 which extends through slots 128 to engage said sleeve. Shaft 86 is counterbored at 130 to receive stem 124 and the slots 128 are of sufficient length to permit the movement of pins 126 to and from sockets 118, to serve as a clutch to secure the parts together. When this clutch means is engaged the operator cannot adjust the tape due to the worm connection with the worm wheel. Stem 124 is provided with a finger grip 125.

Drive sprocket 88 operatively engages an endless chain belt 132 which is operatively positioned about large sprocket wheels 134 and 136 mounted respectively on like shafts 138 and 140. See Figs. 4 and 5.

Bearing plates 142 removably secured to housing 2 by means of screws 144 are bored at 146 and serve to carry bearings 148 which support the outer ends of shafts 138 and 140; the central portion of said shafts are supported by bearings 150 mounted in housing 2. Mounted on shafts 138 and 140 between bearings 148 and 150 is the sprocket wheel 134 which is mounted for free rotation thereon. The inner end portion of shaft 138 is squared at 152 to receive tape reel 162 to rotate therewith. The outer end of shaft 138 is provided with a latch member 154 pivoted at 156. Latch member 154 is adapted to be positioned in alignment with shaft 138 to receive the reel 162 thereover, and then to be turned at right angles thereto to secure the reel against longitudinal movement on said shaft.

Shafts 138 and 140 are driven by sprockets 134 and 136 respectively through ratchet clutches 158 and 160 at a speed sufficient to maintain the tape taught at all times regardless of the relative amount of tape wound on the reel. Each of the ratchet clutches 158 and 160 comprises a central hub member 164 secured by pin 166 to shaft 138 and a ratchet toothed peripheral member 168 mounted on said hub and rotatably driven therewith by means of a frictional spring member 170, whereby there will always be a slippage of the ratchet tooth peripheral member due to the drag of the tape which is

driven at a speed in direct ratio to the speed of the train on the track through the driven sprocket 88, chain 132, sprocket wheels 134 and 136 the hubs of which are provided with sprocket wheels 172 which are respectively operatively interconnected with sprocket wheels 174 and 176 by chain belt 178, see Fig. 4. Referring to Fig. 6 it will be noted that hub member 164 is circumferentially grooved at 180 and that ratchet toothed member 168 is internally grooved at 182. Spring 170 is adapted to be positioned in grooves 180 and 182 to hold the clutch members in operative relation and to maintain the spring in position in the clutch.

Referring to Fig. 4 it will be noted that the ratchet tooth member 168 is toothed for engagement by pawl 184 to be driven by sprocket wheel 134, in an anticlockwise direction. This pawl is urged to the ratcheting position by spring 186 secured to sprocket wheel 134. A pawl 188 pivoted to bearing plate 142 and urged to the engaging position by spring 190 serves to prevent accidental clockwise movement of the member 168. However, as above set forth the tension spring 170 positioned between hub 164 and ratchet toothed member 168 permits a relative adjustment of the ratchet parts sufficient to maintain a predetermined tensioning of the tape 6 during its operation. The toothed member of ratchet 160 is similar to that of ratchet 158 with the ratchet teeth formed so that they will serve to drive the ratchet in a clockwise direction. By means of these two ratchets it is apparent that the tape may be selectively driven to the right or to the left along its path of travel simply by adjusting the lever 50 to cause certain of the driving spur gears to intermesh. When the train is moving along the track in the direction indicated by the arrow on Fig. 3 the belt 6 will be moved in the reverse direction so that on the indicator the town being approached will appear to be moving to the center line of the indicator.

Referring now to Figs. 11, 12, and 13 wherein is shown the drive connection from sprocket wheels 174 and 176 to drive drums 13 and 12 respectively it will be noted that sprocket wheel 174 is rigidly secured to shaft 192 by means of set screw 194. Shaft 192 is rotatably mounted in a bearing 196 mounted in housing 2. The inner end portion 198 of shaft 192 is longitudinally grooved at 200 to receive pin rollers 202. Pin rollers 202 serve to engage and grip the wall 204 of bore 206 of this driving drum into which shaft portion 198 is rotatably fitted. Grooves 200 are of like wedge form and serve with walls 204 and rollers 202 as a clutch whereby the drive drum 13 is driven in one direction and permitted to idle in the opposite direction. It will be noted that the three grooves are so spaced about the periphery of 198 that one of them will always be positioned so as to effect a gripping action to drive the driving drum 13. Referring to Fig. 11 it will be noted that when the clutch member in driving drum 13 is the direction indicated by the arrow tape 6 will be drawn from drum 12, furthermore the clutch in drum 12 will not drive said drum in the direction of the rotation of drum 13 thus permitting it to stand still until such time as the tape becomes sufficiently taut to drive said drum in the same direction as the rotation of driving drum 13 so that the tension of the tape will be regulated by the tensioning spring 170 in clutch 150, see Figs. 5 and 6. The rollers 202 are maintained in proper position by the sleeve 208 positioned between bearing 196 and driving drum 13 and by washer 210 secured to the face of drum 13 by means of a screw 212 and bored in shaft 192.

An electric switch box 214 secured to housing 2 carries a switch arm 216 pivoted intermediate its ends at 218 with its upper end 220 adapted to rest against tape 6 on drive drum 13 to normally hold the spring switch 222 in the open position. The upper end 220 of arm 216 rests on tape 6 in alignment with a series of holes 224 formed in said tape so that when hole 224 registers with said arm 216 said arm will be oscillated to rest against drum 13 and to permit the closing of switch 222.

Another switch box 226 provided with switch arms 232 is operated in like manner as switch arm 222 by a switch arm 216 which is operated by dropping into one of a series of holes 230 formed in tape 6 opposite the series of holes 224.

For further control of the electric circuit shown diagrammatically in Fig. 15, two spaced apart spring switches 234 and 236 are mounted in bracket 48 and are operable by the operating arm 50 as it is moved trans-

versely over bracket 48. Each of these switches has a fixed contact member 238 and a spring contact member 240 which is normally held in the open position. A ball 242 is positioned on top of member 240 to extend above the surface of bracket 48 in the path of operating arm 50, so that as arm 50 is moved over ball 242 it will force 240 down to contact fixed member 238 thus closing switch 234. Switch 236 has a like switch structure which is adapted to be operated in like manner as the operating arm is moved to the right to close said switch. An annunciator 244 is positioned in the electric circuit to indicate the approach of the train to the non stop station where mail is to be delivered or received.

This electric circuit includes suitable power lines 246 and 248. Switches 222 and 232 are joined together by wire 249 and this wire is connected to power line 246 by wire 250. Wire 250 also extends to connect with one terminal of an electric lamp 22 while the other terminal of said lamp is connected by wire 252 to power line 248. A switch 254 is inserted in wire 252 to operate to open and close the circuit. Spring contact member 240 of switch 236 is connected to contact point 236 by wire 238 and the fixed contact 238 is connected by wire 260 to one terminal of the annunciator coil 262, while the other terminal of said coil is connected by wire 264 to wire 252. When switch arm 216 drops into hole 224 onto the periphery of drum 13 the lower portion of the arm will move away from switch 222 and permit it to contact point 256 to close the circuit so that when switch 256 is closed, as shown, current will pass from wire 246 to wires 250, 249, switch 22, wire 258, closed switch members 238 and 240, to wire 260 to coil 262, wires 264 and 252 through closed switch 250 to power wires 248 thus energizing the annunciator whereby signal is given that the train is approaching a non stop station. Switch members 238 and 240 of switch 234 are also connected up with annunciator 244 by wire 266 whereby when arm 216 falls into one of the series of holes 230 onto the periphery of drum 12, switch 232 will make contact with contact point 268 which connects with switch member 240 of switch 234 through wire 270. This switch 234 acts only when the train is running in the opposite direction and the operating arm 50 has been moved to force the switch members 240 and 238 of said switch to the closed position, whereby the annunciator will be operated to announce the approach of the towns from the opposite direction.

The indicia 272 on tape 6 are to indicate the irregularly spaced towns along the railway and the numeral indicia 274 to indicate the number of miles to and from a given station shown on the tape.

A bracket 276 carried by housing 2 is inclined upwardly and forwardly to carry a looking glass 278 to reflect the indicia from tape 6 in the proper readable position to an operator positioned in front of the indicator.

This description clearly sets forth the objects of my invention and what I desire to claim is:

A station indicator for a propelled railway comprising a cabinet adapted to be mounted in said car, a tape carried for longitudinal movement in said cabinet, said tape having longitudinally spaced apart station indicating markers thereon and a pair of holes formed therethrough respectively in oppositely spaced relationship from each of said markers, an electrical circuit including a signalling device and a source of electric power, a pair of switches carried by said cabinet and adapted to be inserted selectively in said circuit, each of said switches having an operating arm, said arms normally being urged against said tape and being held thereby against movement to hold said switches open, driving means for moving said tape in synchronization with the speed of travel of said car, whereby said holes are successively brought into registry with said switch operating arms, said holes permitting movement of said arms to close said switches, manual means for reversing said driving means to reverse the direction of travel of said tape, and switching means disposed in said electric circuit and operable by said reversing means to insert one or the other of said first named switches in said circuit.
